UNITED STATES PATENT OFFICE.

GEORGE T. GREGORY, OF NEW KENSINGTON, AND HENRY W. BURKET, OF ARNOLD, PENNSYLVANIA.

AUTOMATIC COUPLING, FOR MINE-CARS.

1,392,145.

Specification of Letters Patent. Patented Sept. 27, 1921.

Application filed May 16, 1919. Serial No. 297,519.

To all whom it may concern:

Be it known that we, GEORGE T. GREGORY and HENRY W. BURKET, citizens of the United States, residing, respectively, at New 5 Kensington and Arnold, in the county of Westmoreland and State of Pennsylvania, have invented certain new and useful Improvements in Automatic Couplings for Mine-Cars; and we do declare the following 10 to be a full, clear, and exact description of the invention, such as will enable others skilled in the art to which it appertains to make and use the same, reference being had to the accompanying drawings, and to the 15 letters and figures of reference marked thereon, which form a part of this specification.

Our invention relates to automatic couplers for mine cars. It has for its 20 object to provide at one end of the car a link and pin in which the link will be held normally in position for automatic engagement with the coupling pin of an adjacent car when the two cars are brought into 25 coupling relation to each other, said link admitting of being turned when the cars are passing a curve or turn in the track and to be returned to normal position by an associated spring; the opposite end of the 30 car being provided with a gravitating coupling pin adapted to turn on a pivot and to be lifted by engagement therewith of the link of the adjoining car and then to drop into holding position with the link 35 as soon as the coupling is effected, the couplings at the opposite ends being connected one with the other by a bar or plate extending from one coupling to the other and lying along the bottom or floor of the 40 car, and thus contributing to stabilize the couplings at both ends of the car.

To the accomplishment of the foregoing and such other objects as may hereinafter appear the invention consists in the features 45 hereinafter particularly described and then sought to be clearly defined by the claims, reference being had to the accompanying drawings forming a part hereof, and in which—

50 Figure 1 is a side elevation of a mine car, with parts broken away, and illustrating our invention applied;

Fig. 2 is a plan view of the gravitating coupler pin at one end of the car;

Fig. 3 is a vertical section through the 55 same end;

Fig. 4 is an end view of Fig. 3;

Fig. 5 is a bottom plan view of the link and pin coupling end of the car, and showing the spring which holds the link and pin 60 in normal coupling position;

Fig. 6 is a vertical section, through the link and pin coupling end, the pin being in full lines;

Fig. 7 is a plan view of the coupling link;

Fig. 8 is a plan view of the spring which holds the link and pin in normal position, the spring being partly broken away.

In the drawings the numeral 1 designates the body, 2 the bottom or floor, and 3 the 70 wheels of a well known type of mine car, and which may in construction be of any of the standard makes of this type of car.

At one end of the car we provide a link 4 and a coupling pin 5 which will be a permanent fixture attached to the end sill of the car. The link will be formed at one end 75 with a boss or collar 6 in which will be made a seat or recess 7 leading from the opening 8 through which the coupling pin will pass 80 and will rest on the car sill between it and the overhanging end 9 of a plate or bar 10 which will extend from one end of the car to the other end along the car bottom or floor 85 and at the other end will have an overhanging portion 11 extending over the sill at that end and formed at such end with a slot 12 to receive the gravitating pin at that end as hereinafter described. The coupling pin for attachment of the link 4 to the car sill is designated by the numeral 5 and passes rotatably through the overhanging portion 9 of the coupling bar 10 and through the end sill 90 as shown. It is formed with a lug or key 14 which will fit in the seat 7 of the collar 6 of the link, and near its lower end is formed with a key or lug 15 to fit in a seat or recess 16 formed in a plate 17 through which the pin will pass and which will be supported from beneath the bottom of the car, for instance by a bolt 18 passing through an elongated slot 19 at one end of the plate and also by the coupling pin 5 through the end of which, beneath the plate 17, will pass a cot-

ter-pin 20. The plate 17 between its two ends is formed with a reduced neck portion 21 so as to render the same resilient or somewhat elastic so as to perform the function of 5 a spring. The keys or lugs of the coupling pin fitting in the seats or recesses of the coupling link and the tension plate, respectively, will cause the link to be normally held in coupling position so as to be engaged by the 10 gravitating coupling pin of the next car and yet permit the link to swing or turn with the coupling pin when the car is rounding a curve or bend in the track, the spring plate at such time being put under tension so that 15 when the curve has been made the tension plate will tend to resume its normal position and aid in bringing the coupling link into its normal parallel or straight position. Danger in coupling the cars is thus obviated 20 and the prompt automatic coupling of two cars is provided for.

At the other end of the car the coupling pin is in the form of a gravitating pin or dog 22 which is supported in the head or 25 housing 23 by a pin 24 passing through a slot 25 in the pin or dog. The end or tongue 26 of the gravitating pin or dog will fit in the slot 12 of the overhanging portion 11 of the bar or plate 10, and above the end 30 of the tongue 26 the dog is formed with a shoulder 27 designed to bear against a part of the housing and prevent the dog from jumping or being jarred out of the link 4 when the cars are coupled together. The 35 gravitating pin or dog 22 is connected by a chain 28 to the end of a bell crank lever 29 journaled on the end of the car so that when the cars are to be uncoupled the lever is turned to pull forward on the chain and 40 tilt the dog so as to release it from locking position and then lift it out of the link and allow the cars to be uncoupled. When the cars are coupled and under draft the pull is 45 squarely on the head or housing and on the plate or bar which extends from one end of the car to the other, by reason of the gravitating pin or dog bearing against the head or housing and the plate or bar as shown in Fig. 3 of the drawing.

50 By providing one end of the car with the spring held or influenced link and the other with the gravitating dog or pin each car is provided with a full equipment for coupling two or more cars together, and without liability of any necessary parts becoming detached and lost; and the bar which extends from one end to the other of the car and connects the coupling at one end with the coupling at the other gives stability to both 55 couplings and the draft is distributed 60 through the plate or bar and the floor from one end to the other of the car.

One end of the car will be provided with a draft bar 30 secured to the car by bolts 31 so that draft animals or mules may be 65 hitched to the car for drawing the car or train along the track or tramway whenever necessary.

We have described with particularity the preferred details of the several parts but 70 changes may be made without departing from the essentials of the invention.

Having described our invention what we claim is:

1. A car coupling comprising a coupling 75 pin and link, the link having a collar formed with a seat and the pin formed with a key to fit in the seat to connect one to the other to be rotatable together and non-rotatable one relatively to the other, and means coöperating with the pin for normally holding the link in a forwardly projected position.
2. A car coupling comprising a coupling pin and link, and an elastic member for restraining the rotation of the link, the link 85 being formed with a collar, and the pin formed with keys fitting in a seat formed in the collar and the elastic member, respectively.
3. A car coupling comprising a coupling 90 pin and link, and an elastic member for restraining the rotation of the pin; the link being formed with a collar having a key-seat, and the elastic member consisting of a plate attached to the under part of the car 95 and having a reduced portion constituting a resilient neck and formed with an opening for the coupling pin and a key seat, the coupling pin being formed with keys to fit in the key seat of the link-collar and key-seat of the elastic member, respectively.
4. A car coupling comprising a coupling 100 pin and link, and an elastic member for restraining the rotation of the pin; the link being provided with a collar having a key-seat, and the elastic member formed with a key-seat, and the coupling pin formed with keys to fit in the key-seats of the link collar, and elastic member, respectively, and a member overhanging the collar of the link 110 to hold the same in place.

In testimony whereof we affix our signatures in presence of two witnesses.

GEORGE T. GREGORY.
HENRY W. BURKET.
